Des. 198,250
Patented May 19, 1964

198,250

LUGGAGE HANDLE

Joseph Finkelstein, Glenside, Pa., assignor to Philadelphia Handle Company, Camden, N.J., a corporation of New Jersey

Filed Oct. 8, 1963, Ser. No. 76,908

Term of patent 14 years

(Cl. D87—2)

FIG. 1

FIG. 4

5 →

FIG. 2

FIG. 3

FIG. 5

FIG. 1 is a side perspective view of a luggage handle showing my new design;

FIG. 2 is a side elevational view thereof;

FIG. 3 is an end elevational view thereof;

FIG. 4 is a cross-sectional view thereof taken on line 4—4 of FIG. 3; and

FIG. 5 is a cross-sectional view thereof taken on line 5—5 of FIG. 2.

I claim:

The ornamental design for a luggage handle, substantially as shown.
